2,181,322

MEASUREMENT AND CONTROL OF THE
FLOW OF VISCOUS FLUIDS

Harry G. Geissinger, Cleveland, Ohio

Original application August 23, 1934, Serial No.
741,173. Divided and this application January
25, 1937, Serial No. 122,251

15 Claims. (CL. 158—1)

My invention relates to the measurement and control of the flow of viscous fluids, and this application is a division of my co-pending application, Serial No. 741,173, filed August 23, 1934 now Patent No. 2,072,204.

The primary object of the present invention is to provide an improved method and apparatus for controlling oil burning equipment for industrial furnaces.

Other objects will be more apparent as the description proceeds.

In the drawing:

Figure 1 is a sectional plan view of a fuel input valve embodying one form of my invention;

Figure 2 is a vertical section on the line 2—2 of Figure 1;

Figure 3 is a vertical section on the line 3—3 of Figure 1;

Figure 4 is a top plan view of a portion of the apparatus as indicated by the line 4—4 of Figure 2;

Figure 5 is a vertical section at right angles to the section shown in Figure 2 and is taken on the line 5—5 of Figure 4;

Figure 5A is a fragmentary vertical section on line 5A—5A of Figure 4;

Figure 6 is a sectional view on a smaller scale taken on line 6—6 of Figure 1;

Figure 7 is a diagram showing the device of Figure 1 connected to a furnace system;

Figure 8 is a longitudinal section through an equalizer burner valve;

Figure 9 is a fragmentary section of the left-hand portion of the device shown in Figure 2 showing a modified form of throttling valve control;

Figure 10 is a section on the line 10—10 of Figure 3.

The invention as illustrated is in the form of a fuel input valve adapted to deliver oil to a burner system determined by the square root of the pressure of the combustion air supplied to the burners. The construction is of the same general type as illustrated in Figure 6 of my co-pending application, but is provided with additional features adapting the same for insuring an accurate controlling system for an automatically controlled metallurgical furnace.

Referring now to Figure 2, the casing 1 has a central cavity 118 for receiving the operating parts of the metering system. The casing is provided with a removable top 43 to which is attached the parts of the apparatus forming the adjustable orifice and the adjustable resistor. Thus the partition wall 14 is retained in the cap

by the annular sleeve 121 which threadedly engages the cap. The cup-shaped member 122 is now carried by a lifting screw 25 threadedly engaging the boss 150 and having the head end thereof at the upper end of the cap 43 as illustrated in Figure 5. The metering pin 15 is secured to the cup-shaped member by fastening means 123. The diaphragm system 9d, 10, 8d is also similar to that shown in my Patent No. 2,072,204 except that the diaphragm 20d is now omitted.

The inlet 2 is provided with a ball valve 34 and seat 35, and the valve is operated by a lever 32 which is connected to an auxiliary diaphragm 36. The casing 1 is provided with a partition wall 151 forming an inlet chamber 152 into which the fluid from the inlet 2 first passes. The diaphragm 36 has one side thereof subjected to the pressure in the inlet chamber 152 and is secured to the casing by a cap 153 forming a chamber 154 on the opposite side of the diaphragm. A passageway 155 connects the chamber 154 with the central cavity 118 thereby equalizing the pressures in these chambers. Communication between the inlet chamber 152 and the central cavity 118 is provided by means of the pressure valve 37 which, as shown, comprises a tube 156 extending through the partition wall 151 and having a series of radial ports 157. A slide sleeve 158 is arranged within the tube 156 and is adapted to move within the tube by means of the lever 159 which in turn is freely mounted on the shaft 40. The outer end of the lever 159 carries a pin 38 adapted to contact with the center plate of the diaphragm 9d. A spring 39 fixedly secured to the shaft 40 bears against the pin 38 and holds the latter in contact with the center plate of the diaphragm. The shaft 40 extends outwardly through the casing 1 and has fixedly secured thereto a lever 41 which in turn abuts a push rod 42 extending longitudinally beneath the casing. The push rod 42 is adapted to be moved in accordance with the pressure of the air supply or by any other suitable controlling force and the preferred construction will now be described.

The cap 160 which retains the diaphragm 8d in position on the casing has a plurality of lugs 54 extending outwardly therefrom. A ring 162 is mounted on the lugs. A diaphragm 163 extends across the ring 162 and is retained in position by a cap 164 and retaining screws 161 which threadedly engage the lugs 54. The cap 164 is recessed forming a chamber 165 on one side of the diaphragm 163 into which air under pressure may

enter through the port 57. The lugs 54 are grooved to receive the circumference of a split ring 52. The ring terminates at one end in a lug 166 having a threaded aperture for receiving a threaded pin 53. The other end of the ring has a laterally extending portion 167 terminating in the lug 168, spaced from the lug 166 and having an aperture 169 for receiving the end of the pin 53. Thus by adjusting the threaded pin 53 the lugs 166 and 168 may be spread thereby frictionally engaging the ring 52 in the grooved lugs 54. 5 51 is a hinge arranged between the lugs 166 and 168 and using the pin 53 for its pivot. Extending from the hinge is a member 50 which extends 10 in alignment with the center of the diaphragm 163 and has a return bent portion 170 of arcuate shape. The center plate of the diaphragm 163 has a projecting portion 171 adapted to bear 15 against the member 50. The push rod 42 hereinbefore described abuts the arcuate member 170.

With the adjustable hinged arrangement as described, it will be observed that by loosening the threaded pin 53 the ring 52 may be rotatably adjusted in the lugs 54 thereby rotatably adjusting the hinge 51 and consequently changing the effective leverage on the push rod 42. With the parts in the position as illustrated, the effective leverage on the diaphragm 163 and the push rod 42 is the same, but by adjusting the hinge 51 20 rotatively, the leverage effective on the push rod 42 is increased or decreased over that effective on the diaphragm. This adjustment makes it possible to compensate for differences in combustion air pressures in the initial setting of the apparatus. 25

On the cap 164 is arranged a proportioning valve 172 adapted to determine the air pressure in the chamber 165. As shown, this comprises a cylinder 173 having two conduits communicating therewith designated 58 and 59. A piston 60 within the cylinder is so arranged as to simultaneously uncover a portion of each of the conduits and permit communication with the recessed intermediate portion 174 of the piston. The aperture 57 in the cap also communicates with this recessed portion of the piston. An adjustment screw 62 is adapted to move the piston to vary the proportion of the fluid entering the proportioning valve. 35

In order to clear the central cavity 118 of accumulation of gases a suitable relief valve is provided. As shown, the cap 43 is provided with a shouldered vertical passage 175 extending from the cavity 118 into the passageway 75. The passageway 75, as in the preceding examples, extends between the chamber P on the outside of the minor diaphragm 8d and the chamber O above the orifice 4, and consequently communicates directly with the discharge 3 by means of the down-turned passageway 176. The valve 45 is actuated by means of a lever 46 arranged within the central cavity 118 and pivoted on the pin 48. The other end of the lever 46 is provided with a float 47, the arrangement being such that whenever the liquid level falls through an accumulation of gases, the valve 45 is opened and permits such gases to escape through the port 75 and the discharge 3. 50

There is also provided a manually adjustable 70 by-pass from the cavity 118, this being in the form of an adjustable screw 44, the head of which extends through the top of the cap. The lower end of the screw forms a valve cooperating with the conical valve seat 177 to close or open an auxiliary vertical passageway 178. The upper end

of passageway 178 has a laterally extending bore 179 communicating with the port 75. The opening of the by-pass is sometimes advisable in the initial firing of a cold furnace. In the operation of the fuel input valve as thus far described, the fluid enters through port 2, flows past ball valve 34 into the inlet chamber 152 and then passes through the pressure valve 37 into the central cavity 118. The fluid then passes downwardly through the variable channels 126 of the resistor into the cup-shaped member 122, then upwardly through the channels 130 of the resistor. It then flows through the orifice 4 into the chamber O and out through the discharge 3. This flow of fluid creates a tension in the diaphragm system 8d, 10, 9d in the direction of the arrow 105, that is, towards the minor diaphragm 8d. This pressure is then transmitted through the spring 39 to the rod 40 and tends to oscillate the same in one direction. This oscillation, however, is resisted by the force transmitted to the rod 40 by the lever 41 and push rod 42 which, as previously explained, is derived from the air pressure acting on the diaphragm 163. Thus the pressure due to the liquid flow and the pressure obtained from the air flow are balanced against each other through the spring 39 which tends to eliminate slight fluctuations. The free lever 159 which actuates the pressure valve 37 is also responsive to the movement due to the balanced forces above mentioned since the pin 38 attached thereto is intermediate the diaphragm 9d and the spring 39, and therefore exerts a throttling effect between the chamber 152 and the cavity 118. This in turn creates a differential pressure on the diaphragm 36 and actuates the lever 32 to open or close the ball valve 34. It will thus be understood that my device balances the air pressure against the fluid pressure and governs the amount of fluid entering the device accordingly. 40

Figure 7 illustrates diagrammatically a preferred method of utilizing the fuel input valve just described in connection with automatic temperature control mechanism of a metallurgical furnace. It also illustrates two different types of oil 45 burners and the association with a motorized air control energized and directed by thermometric instruments. The instruments themselves are not illustrated, nor is the furnace, since they may be of any suitable type and are not essential to 50 the understanding of the invention.

The combustion air enters through the trunk line 63 from a suitable source and is distributed to the burner 66 through a branch pipe 180 and to burner 66a through branch 181. The oil enters 55 the casing 1 of my fuel input valve through the inlet 2 and leaves through the discharge 3, being distributed to the burner 66 by a conduit 182, equalizer burner valve 69 and conduit 73. It is similarly distributed to burner 66a by conduit 183, equalizer burner valve 69 and conduit 73. The trunk line 63 is provided with a valve 64 mechanically operated by suitable mechanism not illustrated in detail but diagrammatically represented at 65. This form of motor controlled valve 65 is well understood in the art, and the position of the valve is determined by thermometric instruments in the metallurgical furnace.

An air line conduit 67 communicates with the trunk line in advance of the valve 64 and is provided with a manually operable valve 68. One branch from the conduit 67 is connected to the pipe 58 of the proportioning valve previously described. The other pipe 59 of the proportioning valve is connected to the branch air line 180 75

posterior to the valve 64. Thus the pressure effective on the diaphragm 163 of the fuel input valve is some definite proportion of the trunk line pressure and the pressure of the air flowing to the burner. This proportion may be suitably adjusted by changes of the area of the ports covered by the valve 60 of the proportioning valve. The equalizer burner valve 69 is shown in detail in Figure 8. It comprises a cylinder 184 in which a piston 185 is longitudinally adjustable by means of a threaded stem 186 engaging the correspondingly threaded head 187. The piston has a spiral groove 188 in the periphery thereof through which the oil is required to flow from the annular channel 189 to the discharge orifice 190. By rotatably adjusting the piston 185 through the handle 191, the length of the spiral groove between the inlet and discharge may be varied, consequently varying the resistance to the passage of the oil. 72 is a shut-off valve.

In order to understand the operation of the system as illustrated in Figure 7, it should be remembered that the valve 64 will assume predetermined positions by direction of the thermometric instruments, ranging from a wide open position during the starting of the furnace to a closed position when the furnace ceases to be in operation. Intermediate positions of the valve will be obtained in order to exactly regulate the amount of air delivered to the furnace under changing temperature conditions. The quantity of oil passed by the metering control device is determined by some proportion of the combustion air pressure and is not determined solely by the pressure delivered to the burner valve 66. This is for the reason that at times of low combustion rate in the furnace, external air flows into the furnace through burner ports and other leakages. This influx tends to produce an oxidizing atmosphere. To retain the true proportion of air and fuel for ideal combustion, the arrangement which I have illustrated makes it possible to enrich the combustion at low firing rates and to make this enrichment readily controlled by the operator without permitting the operator to alter the normal combustion mixtures during the normal firing of the furnace.

Referring again to Figure 7, it will be apparent that if the valve 64 were closed, air would flow through the pipes 67 and 58 to the proportioning valve and thence through pipe 59 and conduit 180 to the burner 66, although the amount of flow through the proportioning valve is negligible. However, there would still be a definite pressure in the chamber 165 acting on the air pressure diaphragm 163 and this pressure would produce a certain oil flow through the apparatus. It will also be noted that if the valve 64 were wide open, pressures in 58 and 59 would be substantially equal and the pressure effective on the air pressure diaphragm 163 would be the pressure of the burner system. Due to the square root effect of the air pressure, the enrichment adjustment practically disappears at a 50% to 70% fuel input.

In Figure 7 I have also illustrated a second type of burner 66a which is of the dual air type. The secondary air supply is introduced through a conduit 192 from the conduit 68, which in turn receives its supply in advance of the controlling valve 64. The secondary air supply is therefore never under the automatic control.

A modification of the device shown in Figure 2 is illustrated in Figure 9. The only change from the device of Figure 2 is in the form of the

throttling valve which replaces the diaphragm 36, lever 32 and ball valve 34. As shown in this construction, the partition wall 151 divides the cavity 118 from an inlet chamber 152 as in the preceding device. The throttling valve 37 is the same as before but is located at a lower portion of the chamber 152. Instead of the diaphragm 36 there is now provided a piston 193 vertically slideable in a sleeve 194. A port 155 establishes communication between the head of the piston and the central cavity 118. The valve body 195 has an inlet port 196 registering with the fluid inlet 2. The valve consists of a rod 197 having a threaded portion 198 engaging the valve body 195. The valve has a groove 199 therein and the arrangement is such that rotation of the same will expose a variable amount of the groove and thus vary the amount of fluid which can flow from the valve body to the chamber 152. The rotation of the valve is by means of a sprocket 200 on the end of the valve. A chain 201 passes over the sprocket and one end thereof is secured at 202 to the piston, while the other end thereof is attached to a coil spring 203 which in turn is secured to the casing 1 as indicated at 204.

In the operation of the device, fluid entering through the throttling valve 197 passes through the pressure valve 37 which creates a difference of pressure between the chambers 152 and 118, thus moving the piston 193 which in turn rotates the valve 197 and varies the amount of fluid entering chamber 152. It will be noted that the closing of the throttling valve is the result of upward motion of the piston 193 in response to a decrease in the area of the pressure valve 37. This upward motion of the piston reduces the flow through the pressure valve, automatically reducing the effect of the same and anticipates the new position. Such anticipation eliminates "hunting" in the throttling valve. The closing action also creates increase in the counter-pull of the spring 203 cooperating in anticipation effect. It will be noted that movement of the piston 193 does not alter the flow through the metering device of the control.

The fuel input valve of the system connected thereto as illustrated, has many advantages over the prior art. In the first place, the viscosity effect is eliminated in accordance with the principles described in my Patent, 2,072,204, issued March 2, 1937. It should also be noted that the throttling valve in actual control of the flow is self-cleaning, automatically opening to produce a definite flow. The metering orifice and passageways are of such size throughout that granular carbon (which is present in all modern fuel oil) cannot clog the same in contradistinction to present-day devices using small tapered orifices for controlling the oil supply. In my apparatus the quantity of fuel oil delivered to a group of burners is automatically determined by the combustion air pressures whether the variations in pressure are accidental or produced by direct intent. My invention meets the modern tendency towards a "floating" combustion rate. In conjunction with motorized air valves under the direction of thermometric instruments, my metered controls will automatically deliver fuel in proportion to the air.

In my device, the air directed force may be standardized to meet the variable conditions of combustion air pressures found in different plants. When fuel oil of very low viscosity is used, the standard push rod pressure or the rod 75

62 may be reduced, larger metering systems equalizing the output.

5 My device provides for the enrichment of the combustion mixture at low combustion rates without affecting the adjustment under normal conditions. This is by means of the proportioning valve 62, but as previously explained, this enrichment is entirely nullified at higher rates because of the equalization of pressures on the 10 opposite sides of the throttling valve 64 where the latter is open. My device further provides through modification of the effective controlling air pressure, for the necessity of delivering a defined quantity of fuel corresponding to the constant air supply to dual type air burners as illustrated in 66a.

20 The equalizer burner valves used in conjunction with the individual burners of a group compensate for the difference in resistance to oil flow because of different lengths of pipe and other factors. This compensation is provided without the use of needle valves, and in such a manner that the passages cannot become clogged. The equalizer has a back pressure proportioned to the flow 25 and offers material opposition at low rates.

30 It should be understood that while Figure 7 shows two burners under the same control, the number of burners may be varied at will, depending upon the furnace construction.

35 It will be noted that in the construction illustrated in Figures 1 and 2, the orifice rod 15 has a variable groove therein and the resistor is made up of two parts, one having variable channels, and the other having channels of fixed dimensions.

40 It will be evident that the resistance factor R of the orifice will vary with the area and stroke of the system, and that the factor r of the resistor must vary in proportion therewith. The resistance developed by the channels 130 is proportional to that of the maximum area of the orifice 4. When the rod 15 and the cup-shaped member 122 are in their lowermost positions, the widths of the channels 126 are developed so that the additional resistance, due to the decreasing area of the 45 orifice, will add a proportional resistance to the resistor system. The raising of the rod 15 and the cup-shaped member 122 therefore both increases the length of the resistor and reduces the primary area of the system. In order to calibrate 50 the instrument shown in Figure 2, the adjustable core 128, which has the fixed resistor channels 130 therein, is adjusted longitudinally with respect to the sleeve 121 while the cup-shaped member 122 is 55 in its uppermost position until the proper proportion between the resistance of the fixed channels 130 and the variable channels 126 is obtained, this proportion depending upon the maximum and minimum orifice areas due to the extreme movement of the rod 15. When the desired proportion 60 is obtained, the core 128 is suitably secured to the sleeve 121 by suitable securing means. The rod 15, which is threadedly secured to the cup-shaped member 122, is thereupon adjusted so that 65 the resistance factor R is exactly proportional to the resistance factor r , the latter being the summation of the fixed resistance of the channels 130 and the variable resistance of the channels 126. When the proper adjustment is obtained, the rod 70 is fixed to the member 122 by the pin 123. This method of calibration insures a very accurate apparatus which will exactly nullify the viscosity effect of the fluid. It is also possible to determine 75 these factors mathematically.

75 One of the features of the fuel input valve of

Figure 2 is that the position of the valve is determined by the balancing of the force due to the flow of the fluid with an external directing force and utilizing any unbalance of the system for automatic control. As shown, the directing force 5 is the combustion air pressure, but the invention in its broader aspects may utilize any other force such, for example, as the steam pressures in oil fired power plants. It is therefore to be understood that the invention is not to be considered as 10 limited to the specific embodiments herein described, but the scope of the invention is to be construed by the claims appended hereto.

What I claim as my invention is:

1. A system for controlling combustion of fluid 15 fuel comprising a burner, an air line and a fluid fuel line connected thereto, a valve in said air line adapted to regulate the air supply to said burner, a valve in said fluid fuel line adapted to regulate the fluid fuel supply to said burner, means for 20 regulating said fluid fuel valve by the unbalance between a pressure derived from the fluid flow and a pressure derived from said air line, conduits from said air line on opposite sides of said air valve connected to said fuel regulating means 25 whereby air pressure anterior to said air valve is effective on said fuel regulating means in order to increase the ratio of fuel to air when said air valve approaches the closed position while maintaining the normal ratio when said air valve is 30 open.

2. A system for controlling combustion of liquid fuel comprising a burner, an air line and a liquid fuel line connected thereto, a valve in said air line adapted to regulate the air supply to said burner, a valve in said liquid fuel line adapted to regulate the liquid fuel supply to said burner, said fuel valve comprising a passageway for the liquid fuel having a constricted area, therein and having means therein for creating a resistance to flow 40 which is a function of length, a movable element having pressure responsive faces of different effective areas, means for urging said element in opposite directions by the pressures within said passageway on opposite sides of said constricted 45 area on the one hand and on opposite sides of said resistance means on the other hand, thereby obtaining a net force due to the flow of the fluid through said passageway, a pressure responsive element adapted to exert a force on said movable 50 element in opposition to said net force and conduits connecting said pressure responsive means with said air line on opposite sides of said air valve whereby air pressure anterior to said air valve will be proportionately effective on said 55 movable element when said air valve approaches closed position thereby enriching the combustion mixture.

3. In an apparatus of the class described, pressure responsive means, a lever operatively engaging said pressure responsive means, a hinged fulcrum for said lever, means for rotatively adjusting said hinged lever, said lever having an arcuate portion extending circumferentially, and a push rod engageable with said arcuate portion and 65 adapted in different rotative positions of said hinge to receive a different proportion of the force exerted by said pressure responsive means.

4. In apparatus of the character described, condition responsive means adapted to exert a force 70 variable in accordance with the value of said condition, movable means associated with said condition responsive means adapted to be acted upon by said condition responsive means, and adjustable means interposed between said condition 75

- responsive means and said movable means, the adjustment of said adjustable means providing for transmitting a predetermined proportion of said variable force to said movable member, said 5 adjustable means comprising a lever having an arcuate arm, and a second arm extending to the axis of said arcuate arm, and being adjustable about said axis, said condition responsive means engaging said second arm adjacent said axis, and 10 said movable means engaging said arcuate arm, whereby said lever will transmit a reduced or multiplied force to said movable member, said force variable in accordance with the force exerted by said condition responsive means.
- 15 5. A system for controlling combustion of fluid fuel comprising a burner, an air line and a fluid fuel line connected thereto, a valve in said air line, a valve in said fuel line, control means for said fuel valve, said control means comprising pressure responsive means, a conduit providing for a flow of air around said air valve, a regulating valve in 20 said conduit, said pressure responsive means connected to said conduit posterior to said regulating valve.
- 25 6. A system for controlling combustion of fluid fuel comprising a burner, an air line and a fluid fuel line connected thereto, a valve in said air line, a valve in said fuel line, control means for said fuel valve, said control means comprising pressure responsive means, a conduit providing for a flow of air around said air valve, a pair 30 of cooperating valves in said conduit spaced to form a chamber therebetween, said pressure responsive means connected to said chamber.
- 35 7. A system for controlling combustion of fluid fuel comprising a burner, an air line and a fluid fuel line connected thereto, a valve in said air line, a valve in said fuel line, control means for said fuel valve, said control means comprising pressure responsive means, a conduit providing for a flow of air around said air valve, a pair of 40 cooperating valves in said conduit spaced to form a chamber therebetween, said pressure responsive means connected to said chamber, and means for adjusting said cooperating valves to vary the pressure in said chamber.
- 45 8. A system for controlling combustion of fluid fuel comprising a burner, an air line and a fluid fuel line connected thereto, a valve in said air line, a valve in said fuel line, control means for said fuel valve, said control means comprising pressure responsive means, a conduit providing for a flow of air around said air valve, a pair of 50 cooperating valves in said conduit spaced to form a chamber therebetween, said pressure responsive means connected to said chamber, and means for simultaneously and oppositely adjusting said cooperating valves to vary the pressure in said chamber.
- 55 9. A system for controlling combustion of fluid fuel comprising a burner, an air line and a fluid fuel line connected thereto, a valve in said air line, a valve in said fuel line, control means for said fuel valve, said control means comprising pressure responsive means, means for applying a 60 pressure to said pressure responsive means in accordance with the flow and viscosity of said fuel, so as to maintain the flow of fuel constant irrespective of viscosity, means for applying a second pressure to said pressure responsive means comprising a conduit connected in parallel to 65 said air valve, and providing for a flow of air therearound, a pair of cooperating valves in said conduit spaced to form a chamber therebetween, said pressure responsive means operatively connected to said conduit intermediate said orifices, and means for simultaneously and oppositely adjusting said cooperating valves to vary the pressure in said chamber.
- 70 10. A system for controlling combustion of fluid fuel comprising a burner, an air line and a fluid fuel line connected thereto, a valve in said air line, a valve in said fuel line, control means for said fuel valve, said control means comprising pressure responsive means, means for applying a 75 pressure to said pressure responsive means in accordance with the flow and viscosity of said fuel, so as to maintain the flow of fuel constant irrespective of viscosity, means for applying a second pressure to said pressure responsive means comprising a conduit connected in parallel to said air valve, and providing for a flow of air therearound, a pair of cooperating valves in said conduit spaced to form a chamber therebetween, said pressure responsive means operatively connected to said chamber.
11. A system for controlling combustion of fluid fuel comprising a burner, an air line and a fluid fuel line connected thereto, a valve in said air line, a valve in said fuel line, control means for said fuel valve, said control means comprising pressure responsive means, means for applying a 80 pressure to said pressure responsive means in accordance with the flow and viscosity of said fuel, so as to maintain the flow of fuel constant irrespective of viscosity, means for applying a second pressure to said pressure responsive means comprising a conduit connected in parallel to said air valve, and providing for a flow of air therearound, a pair of cooperating valves in said conduit spaced to form a chamber therebetween, said pressure responsive means operatively connected to said chamber, and means for adjusting said cooperating valves to vary the pressure in said chamber.
12. A system for controlling combustion of fluid fuel comprising a burner, an air line and a fluid fuel line connected thereto, a valve in said air line, a valve in said fuel line, control means for said fuel valve, said control means comprising pressure responsive means, means for applying a 85 pressure to said pressure responsive means in accordance with the flow and viscosity of said fuel, so as to maintain the flow of fuel constant irrespective of viscosity, means for applying a second pressure to said pressure responsive means comprising a conduit connected in parallel to said air valve, and providing for a flow of air therearound, a pair of cooperating valves in said conduit spaced to form a chamber therebetween, said pressure responsive means operatively connected to said conduit intermediate said orifices, and means for simultaneously and oppositely adjusting said cooperating valves to vary the pressure in said chamber.
13. A system for controlling combustion of fluid fuel comprising a burner, an air line and a fluid fuel line connected thereto, a valve in said air line, a valve in said fuel line, control means for said fuel valve, said control means comprising pressure responsive means, a conduit providing for a flow of air around said air valve, a regulating valve in said conduit, said pressure responsive means connected to said conduit posterior to said regulating valve, and an adjustable lever connected between said pressure responsive means and said fuel valve to vary the effectiveness of said pressure responsive means.
14. A system for controlling combustion of fluid fuel comprising a burner, an air line and a fluid fuel line connected thereto, a valve in said air line, a valve in said fuel line, control means

for said fuel valve, said control means comprising pressure responsive means, a conduit providing for a flow of air around said air valve, a regulating valve in said conduit, said pressure responsive means connected to said conduit posterior to said regulating valve, and an adjustable lever connected between said pressure responsive means and said fuel valve to vary the effectiveness of said pressure responsive means, said lever having an arcuate arm and second arm extending to the axis of said arcuate arm, said lever being adjustable about said axis, said pressure responsive means engaging said second arm adjacent said axis, a member engaging said arcuate arm and transmitting a controlling force to said fuel valve.

15. A system for controlling combustion of fluid fuel comprising a plurality of burners, an air supply means including a trunk with an air valve therein, and a branch to each burner, a fuel supply means including a main, a fuel valve therein, and a branch to each burner, control means for said fuel valve comprising pressure responsive means, a conduit providing a flow of air around said air valve, a regulating valve in said conduit, said pressure responsive means connected to said conduit posterior to said regulating valve, and means in at least one of said fuel branches providing a fluid channel of variable length but of uniform cross section, and means for varying the length of said channel. 10 15

HARRY G. GEISSINGER.
